UNITED STATES PATENT OFFICE.

LYMAN B. LANGWORTHY, OF CHICAGO, ILLINOIS.

SHEET PILE.

Application filed September 20, 1923. Serial No. 663,833.

This invention relates to improvements in sheet piles. By the use of my improved sheet piles it is possible to make a very tight wall such as is used in making caissons, 5 coffer-dams, retaining walls and the like. My improved piles may be easily driven or otherwise put into position and are so constructed that in driving a pile it will stay close to the adjacent pile. With many other 10 forms of sheet piles it is very difficult to keep the lower ends from separating. My improved piles are also provided with means for interlocking the lower ends after the piles are in position. Other features and 15 advantages of my sheet piles will appear as I proceed with my specification.

In that form of device embodying the features of my invention shown in the accompanying drawings,

20 Figure 1 is a view in front elevation of two sheet piles showing the same, for purposes of illustration, made of concrete,

Fig. 2 is a top plan view of the same,

25 Fig. 3 is a view in elevation of the lower part of the edge of one of the piles showing the pocket used in interlocking the lower ends of the piles,

Fig. 4 is a similar view of the opposite edge showing the hook or interlocking member adapted to go into the pocket,

30 Fig. 5 is a vertical sectional view of a part of the lower ends of two adjacent piles showing the method of interlocking, the view being taken as indicated by the line 5 of Fig. 7,

Fig. 6 is a vertical sectional view of the lower end of one of the piles showing the jet arrangement,

35 Fig. 7 is a view taken as indicated by the line 7 of Fig. 6, and

Fig. 8 is a bottom plan view of the end of one of the piles.

As shown in the drawings, 10, 10 indicate 40 sheet piles adapted to be driven adjacent each other to form sheet piling. Since the piles are similar, I will describe in detail but one. The pile 10 is here shown as made of concrete, although it is obvious that it may be made of any other suitable material.

45 The concrete may be reinforced or not as desired. The pile is substantially rectangular in shape and provided at one of its vertical side edges with a groove 11. This groove 11 terminates a 50 short distance from the bottom of the pile

as indicated by 11^a and the corner is beveled as indicated by 12. The lower edges of the front and back faces are also slightly beveled as indicated by 13. The opposite edge of the pile 10 is provided with two longitudinal 55 ridges 14 slightly concave between as indicated by 15. The two ridges 14 are adapted to go into one of the grooves 11 of an adjacent pile when the piles are in position leaving a channel between the piles substantially circular in cross section. After the piles are in position, this channel may be grouted or cemented or filled with cementitious material in any desired manner in order to more firmly bond the piles together 60 and make a tight joint.

At the bottom of the channel 11 there is mounted in the side of the pile a flat bar 16 which slants upwardly to form the pocket 16^a at the bottom of the channel. The bar 16 is bent at 16^b and its horizontal part as indicated by 16^c is embedded in the concrete to hold it firmly in position. The exposed end of the bar 16 which forms a pocket is also supported by a strap 17 which 70 passes around the bar 16 and has its ends as indicated by 17^a embedded in the concrete to hold it firmly in position.

The opposite side edge of the pile has 75 near its lower end an outwardly and downwardly projecting hook or interlocking member 20 which is here shown as T-shaped in cross section in order to give rigidity. This member has its upper end embedded in the concrete of the pile and is additionally supported by means of the strap 21 which 80 extends around it and has its ends embedded in the concrete as indicated by 21^a.

In setting a pile, the hook 20 slides downwardly in the channel 11 until it engages with the member 16 and seats in the pocket 16^a, thus interlocking the lower ends of the piles. Two piles with the lower ends thus interlocked are clearly shown in Figs. 5 and 7.

The following means are provided for 100 assisting in properly locating the piles. The beveled corner 12 operates to assist in keeping the lower end of a pile close to the adjacent pile as it is being put into position. Besides this, it is to be noted each pile is 105 provided with three jet holes as indicated by 30, 31 and 32. All of these jet holes communicate with a common supply pipe 33 which opens at 34. Any suitable means may be used for introducing water under pres- 110

sure into the opening 34. The jets from the holes 31 and 32 issue directly downwardly. The jet from the hole 30 issues downwardly and to the side toward the adjacent pile which was previously set. This jet from the hole 30, it will be noted, will therefore direct a stream into the channel 11 of the adjacent set pile and keep this channel free to permit the movement therein of the hook 10. Issuing to the side and downwardly it will also remove all obstructions between the two piles and cause the lower end of the descending pile to hug the next adjacent pile which was just previously set.

15 While I have shown and described certain embodiments of my invention, it is to be understood that it is capable of many modifications. Changes, therefore, in the construction and arrangement may be made 20 without departing from the spirit and scope of the invention as disclosed in the appended claims, in which it is my intention to claim all novelty inherent in my invention as broadly as possible in view of the prior 25 art.

What I claim as new and desire to secure by Letters Patent is:

1. A sheet pile having a longitudinal groove at one edge, a tapered pocket at 30 the lower end of the groove, and an interlocking member at the lower end of the opposite edge, said interlocking member adapted to travel in the groove of an adjacent set pile as the pile is driven downwardly and adapted to seat in the tapered pocket of said adjacent set pile as it reaches the end of the groove to draw the ends of the piles together.

2. A sheet pile having a longitudinal 40 groove at one edge, a tapered pocket at the lower end of the groove, and an interlocking member at the lower end of the opposite edge, said interlocking member adapted to travel in the groove of an adjacent set pile as the pile is driven downwardly and adapted to seat in the tapered pocket of 45 said adjacent set pile as it reaches the end of the groove to draw the ends of the piles together, said pile having a jet hole at the 50 end adapted to issue a stream of liquid into

the groove of said adjacent set pile as the pile is driven downwardly.

3. A sheet pile having a longitudinal groove at one edge, a tapered pocket at the lower end of the groove, and an interlocking member at the lower end of the opposite edge, said interlocking member adapted to travel in the groove of an adjacent set pile as the pile is driven downwardly and adapted 55 to seat in the tapered pocket of said adjacent set pile as it reaches the end of the groove to draw the ends of the piles together, said pile having two jet holes at its lower end, one of said jet holes adapted to issue a stream of liquid into the groove of an adjacent pile as the pile is driven downwardly and the other jet hole adapted to issue a stream substantially straight downwardly.

4. A sheet pile having a longitudinal 70 groove at one edge, a pocket at the lower end of the groove, an interlocking member at the lower end of the opposite edge adapted to travel in the groove of an adjacent set pile as the pile is driven downwardly and adapted to seat in said pocket as it reaches the end of the groove, and a jet hole near the lower end of the pile adapted to issue a stream of liquid into said groove of said adjacent set pile as the pile is driven 75 downwardly.

5. A sheet pile having a longitudinal groove at one edge, a pocket at the lower end of the groove, an interlocking member at the lower end of the opposite edge adapted to travel in the groove of an adjacent set pile as the pile is driven downwardly and adapted to seat in said pocket as it reaches the end of the groove, said pile having a jet hole near the lower end adapted 80 to issue a stream of liquid into said groove of said adjacent set pile as the pile is driven downwardly, said jet hole also adapted to issue a stream of liquid into the pocket of the adjacent set pile as the pile being driven 85 nears the end of its travel.

In witness whereof, I have hereunto set my hand this 28th day of August, 1923.

LYMAN B. LANGWORTHY.
